UNITED STATES PATENT OFFICE.

EDWIN A. JOHNSON, OF ALLEGHENY CITY, PENNSYLVANIA.

SASH-FASTENER.

SPECIFICATION forming part of Letters Patent No. 315,294, dated April 7, 1885.

Application filed September 18, 1884. (Model.)

To all whom it may concern:

Be it known that I, EDWIN ALFRED JOHNSON, of Allegheny City, in the county of Allegheny and State of Pennsylvania, have invented a new and Improved Sash Lock and Fastener, of which the following is a full, clear, and exact description.

The object of my invention is to provide a new and improved device for locking the upper and lower sashes of a window firmly together and to the window-frame, and also for locking them in place when partly opened, thus preventing rattling, permitting ventilation, and offering increased security against burglars.

The invention consists in a casing adapted to be secured on one end of the top rail of the bottom sash, and containing a sliding bolt projecting from one end of the casing and a swinging hook-bolt projecting from one side, both bolts being operated from the same knob, and the sliding bolt engaging with an apertured strip on the window-frame stile and the hook-bolt engaging with a notched plate or strip on the upper sash side rail.

Reference is to be had to the accompanying drawings, forming a part of this specification, in which similar letters of reference indicate corresponding parts in all the figures.

Figure 1 is a perspective view of my improved sash lock and fastener, showing it applied. Fig. 2 is a plan view of the under side, the plate of the casing being removed. Fig. 3 is a perspective view of the bolt for locking the sashes together. Fig. 4 is a perspective view of the bolt for locking the lower sash to the casing. Fig. 5 is a face view of the apertured plate on the frame, jamb, or pulley-stile. Fig. 6 is a face view of the notched plate on the upper sash. Figs. 7, 8, and 9 are modified devices for the same purposes.

The flat casing A, formed of a rim and a top and a bottom plate held together by screws, is provided with an end opening, B, and a side opening, C. A sliding bolt, D, preferably having a squared end, is held in the casing and projects through the end opening, B. A pin, E, having a removable handle-knob, E', projects from the bolt D through a U-shaped slot, F, in the top of the casing, the shanks of the slot being inclined to the cross-piece to lock the bolt in place. A spring, G, secured in the

casing, rests and presses against the grooved inner end of the sliding bolt D, and presses the same outward, and also presses the pin E into the shanks of the slot F. A horizontally-swinging bolt, H, pivoted in the case, projects through the side opening, C, and has a right-angled upturned hook, J, with a beveled face formed on its outer end. A pin, K, projecting from the bolt H, passes into a diagonal or inclined slot, L, in the bolt D.

In the pulley-stile M a plate or strip, N, is countersunk, which is provided at regular intervals with apertures O, for receiving the outer end of the bolt D; or in place of the strip N a series of plates, N', may be provided at suitable intervals, each plate N' having a central aperture or notch, O', in its lower edge.

On the inner surface of the corresponding side rail, P, of the top sash a strip, Q, is secured in such a manner that its inner edge projects beyond the inner edge of the side rail, or is flush with a rail suitably recessed, the strip Q having notches R in its free or inner edge at intervals corresponding with the apertures of the strip N.

In place of the strip Q a series of plates, Q', may be used, having side notches, R'.

The casing A is fastened to the top rail, S, of the bottom sash at one end.

The operation is as follows: The pin E is always at the end of one of the shanks of the slot F, where it is held by the spring G. To unlock the sashes, the pin E is pressed out of the slot F of the shank in which it is located, and the bolt D is withdrawn from the apertures in the stile, and the pin E is passed into the other shank of the slot F to hold the bolt withdrawn. At the same time the bolt H is swung from the strip Q by the action of the end of the slot L on the pin K. To lock the sashes, the pin E is released, and by the action of the spring is moved in the inverse direction. The bolt D locks and holds the bottom sash in the desired position, and the hook-bolt H, engaging with the notched plate on the top sash, locks the top sash to the bottom sash, and by the beveled face of the hook draws them closely together when closed or when partly opened, thus securing the objects in view with simplicity of parts, cheapness of construction, and facility of operation.

Having thus fully described my invention, I

claim as new and desire to secure by Letters Patent—

1. The combination, with a swinging hook-bolt pivoted at one end to a base-plate or casing and projecting therefrom at the other end, of a sliding bolt having its outer end guided to pass beyond the end of the base-plate or casing and its inner end pivoted to the swinging bolt by a joint, as described, whereby the two bolts may be moved together, either by the other, substantially as herein shown and described.

2. The combination, with the casing A, having an end opening, B, and a side opening, C, of the sliding bolt D, having a slot, L, the pin

E, projecting from the bolt D through the U-shaped slot F in the top of the casing, the spring G, and the swinging bolt H, provided with the pin K, projecting through the slot L, substantially as herein shown and described. 20

3. The combination, with a sash, of a notched plate or strip secured to the inner surface of one side rail, the notched edge of the strip or plate projecting from or being flush with the inner edge of the rail, substantially as herein shown 25 and described.

EDWIN A. JOHNSON.
